UNITED STATES PATENT OFFICE.

JOSEPH W. WOODS, OF BOSTON, MASSACHUSETTS.

DESIGN FOR TEXTILE FABRIC.

SPECIFICATION forming part of Design No. 19,087, dated May 7, 1889.

Application filed April 4, 1889. Serial No. 306,018. Term of patent 7 years.

To all whom it may concern:

Be it known that I, JOSEPH W. WOODS, a citizen of the United States, residing at Boston, in the county of Suffolk and State of Massachusetts, have invented and produced a new and original Design for Textile Fabrics, of which the following is a specification, reference being had to the accompanying drawing, forming a part thereof.

10 The figure herewith submitted fully illustrates my design.

The characteristic or leading features of my

design consist in the wavy strips of contrasting colors extending diagonally across the face of the rectangular goods, and the whole 15 face of the goods studded with stars, as shown in the drawing.

I claim—

The design for textile fabric herein shown and described.

JOSEPH W. WOODS.
